J. LOUIS REYNOLDS, OF LONG ISLAND CITY, NEW YORK, ASSIGNOR, BY MESNE ASSIGNMENTS, TO ELECTRICAL RESEARCH PRODUCTS, INC., A CORPORATION OF DELAWARE.

SOUND-REPRODUCING SYSTEM.

Application filed May 24, 1927. Serial No. 193,862.

This invention relates to electrical controlling systems and apparatus, and in particular to methods and means for controlling artificial sound reproduction.

5 In sound recording and reproducing systems employing mechanical media sound records such, for example, as the well-known wax disc type, because of the mechanical characteristics of the disc material itself and partly because of the methods of engraving a record in the disc, there are introduced extraneous characteristics which are detrimental to proper reproduction. These undesirable mechanical imperfections in the disc 10 material give rise in the reproducing process to what may be generally described as "surface noise." It is well known in artificial reproducing systems employing this type of record that the deleterious effects of surface noise are not constant throughout the 15 frequency range of the sounds reproduced. It has been found that the surface noises themselves have a frequency range which is most predominant and objectionable above 20 2000 cycles per second. It is also known that a certain amount of surface noise may be present in a reproduced program without materially affecting the pleasing quality of the reproduction. In other words, while the 25 proportion of undesirable characteristics in the wax record to the sound record characteristics is a fixed quantity so far as each individual record is concerned, in the reproducing process the relative proportions so far as their effect on the reproduced program is concerned, 30 varies with the volume of reproduction required. That is to say, we may characterize the inherent surface characteristic of the record material itself as "manufactured surface noise" which, during the reproducing process, gives rise to "reproduced surface 35 noise." As hereinabove mentioned, the ratio of the "reproduced surface noise" to the actual program to be reproduced must never 40 exceed a predetermined value if the pleasing quality of the program is not to be marred.

It has been found that this so-called "allowable ratio" of surface noise to program varies with the general level of volume at 45 which the reproducing system is operated. Heretofore means have been proposed for reducing the effects of surface noise on the reproduction by employing fixed electrical networks or "equalizers," by means of which the

proportionate effects of surface to actual 55 program are constant, and the maximum allowable ratio is reached at a certain volume level. Above that level the ratio of surface noise to sound program must be reduced if a pleasing reproduction is to be maintained, 60 that is, the sound currents must be subjected to greater equalization. Equalization of this character results in the sacrifice of certain frequency components in the reproduction sounds. For very low volume reproduction 65 actual ratios of surface noise to sound program may be much higher than for loud volume reproduction, that is to say, for low volume reproduction, the necessary equalization is less than for loud volume reproduction. 70 Consequently, for low volume reproduction using a fixed equalizer for surface noise, the over-all frequency distortion for a given record is a minimum. As the volume of reproduction is increased this distortion 75 also increases. Expressing it in another manner, for a given record, the amount of equalization necessary to give maximum pleasing quality and minimum disturbance from surface noise, is a function of the volume 80 of reproduction. Hence, to maintain the most desirable quality of reproduction at any desired volume, means must be provided for accordingly varying the degree of equalization. 85

It is therefore one of the principal objects of the present invention to provide an electrical sound reproducing system wherein the allowable ratio of surface noise to desired sound is varied in accordance with the volume 90 of reproduction.

A feature of the invention relates to the means for varying the characteristics of an equalizer in accordance with the desired volume of reproduction. 95

A still further feature of the invention pertains to means for simultaneously varying the gain of a sound reproducing amplifier and for adjusting the characteristics of a "surface noise" equalizer. 100

A further feature of the invention relates to an artificial sound reproducing system using mechanical media sound records and adjustable electrical networks which may be varied by a single manipulation to maintain in a sound reproducer the faithfulness of reproduction independent of volume. 105

Other features and advantages not specifi-

cally pointed out will be revealed after a consideration of the following detailed description and as pointed out in the appended claims.

5 Referring to the drawing, Fig. 1 shows a characteristic curve illustrating the manner in which the allowable ratio of surface noise to desired sound varies with the volume of sound produced by an electro-mechanical 10 sound reproducer.

Fig. 2 shows a series of curves illustrating the gain-frequency characteristics of a reproducing system at various volume levels.

15 Fig. 3 shows the invention as applied to a reproducing system employing disc type records.

Figs. 4 and 5 are modifications of the system disclosed in Fig. 3.

In artificial sound reproducing systems 20 employing mechanical media sound records, it is desirable that the sound cutting in the record blank material vary solely in accordance with the characteristics of the sounds to be reproduced. Two methods for recording sounds in this type of record blank are 25 known, respectively, as the "lateral cut method" and the "hill and dale method." Whichever type of record is desired it is the usual practice to form the groove by means 30 of a cutting tool which is actuated by a sound responsive device. At times, due to imperfections in the master record surface; for example, that due to varying degrees of hardness at different points on the surface as 35 well as that due to the uneven surface structure of the material itself, it is not always possible to produce a cutting which has characteristics faithfully corresponding to the sounds recorded. It will be appreciated, 40 therefore, that in the recording process alone, the master record will show variations in sound cutting which bear no relation to the sound being recorded. In the intermediate process between the actual cutting and the 45 formation of the final wax record, other causes are effective to produce additional undesired surface characteristics so that in the actual record blank as used for reproduction, the surface of the sound cutting 50 may, under microscopic examination, show marked undesirable variations. These latter variations assume such importance that with the present type of amplifying apparatus available it is very difficult to record and 55 reproduce with any degree of faithfulness sounds in the frequency ranges above 5000 cycles per second, since it is at this frequency that the undesirable effects, due to the surface characteristics of a record blank, appear to predominate.

60 This variation is shown by curve 100 in Fig. 1 of the drawing wherein it is seen that the allowable ratio of surface noise to useful sound, so far as an auditor is concerned, must 65 be least when the total volume of sound is a

maximum, and conversely, the allowable ratio may be comparatively larger when the volume approaches zero.

The actual ratio of surface imperfections to sound cutting is, for a given record, fixed, 70 but as pointed out hereinabove, the effects so far as reproduction is concerned, are a function of the volume of sound required, and the allowable ratio during reproduction varies. The manner in which this allowable 75 ratio varies is illustrated in the curve of Fig. 1 wherein the ordinates represent volume of reproduced sound expressed in terms of amplifier gain, and the abscissae represent the 80 allowable ratio of surface noise to useful sound. From an inspection of Fig. 1 it will be seen that at high volume reproduction, the allowable ratio is very small, while for low volumes the allowable ratio is very large. Physically, this means that for low volume 85 reproduction the mechanical imperfections in the record surface produce substantially no deleterious effects upon the reproduction, while at high volumes these imperfections assume greater and greater importance in 90 disturbing the faithfulness of reproduction. This variation in the effects of surface noise with volume therefore requires a corresponding variation in the amount of equalization necessary to produce a pleasing performance. 95

Referring to Fig. 2, there are shown three sets of curves representative of the manner in which the transmission amplifying system must be varied at different volume levels. 100 The ordinates of the curves of Fig. 2 represent degrees of reproduction volume in terms of amplifier gain, while the abscissae represent frequencies of the component amplified currents. Were the record surfaces free 105 from imperfections, the corresponding characteristics of the transmission system for faithful reproduction would obviously be straight, as represented by curves A, B and C of Fig. 2. As pointed out hereinabove, however, the mechanical imperfections or surface noise in the record, while substantially negligible in the lower end of the frequency spectrum, begins to assume prominence as 110 the frequency rises above 2000 cycles per second. Accordingly, the transmission characteristics of the amplifying system must drop off as the higher frequencies are passed. For example, for low volume reproduction, it will 115 be necessary to adjust the constants of the amplifier network to give a transmission characteristic represented by curve A'. Similarly, for medium volume reproduction, the network would have to produce the characteristic represented by curve B', and similarly for large volumes. Any well-known 120 type of attenuating network for producing the characteristics desired may be employed, typical networks for producing these characteristics being illustrated in Figs. 3, 4 and 5 125 130

of the drawing. Heretofore, equalizing networks of this character have been used, but these networks have generally been designed to effect equalization at only a particular 5 volume of reproduction. By the present invention this equalization is made variable so that, as the volume is increased, the amount of equalization is correspondingly increased to take care of the increasing effects of surface noise.

Referring to Fig. 3, the invention is shown applied to a sound reproducing system of the general character disclosed in my copending application Serial No. 180,323, filed April 1, 15 1927. The numeral 1 represents a phonograph turntable upon which is mounted for rotation therewith the wax disc 2 having a continuous cutting thereon corresponding to the sound to be reproduced, said cutting being preferably of the "lateral" type. An electromechanical translating device 3 is adapted to be actuated by the associated stylus 4 and generates voltages corresponding to the varying degrees of cutting in the record blank 20 surface. These currents are then impressed upon the terminals of the artificial line AL which may be of the character disclosed in my application Serial No. 180,323 hereinabove referred to. The currents passing 25 through the artificial line are more or less attenuated according to the length of line included in circuit with the device 3 and the input circuit of the electron discharge amplifier. This input circuit is associated with the 30 line AL by means of the brushes 5 and 6 which may be moved to vary the attenuation. For a description of the manner in which an artificial line of the character shown may be utilized to control the energy level of the 35 sound-modulated currents reaching the amplifier 7, reference may be had to my copending application Serial No. 180,323. For the present description it will suffice to say that the amplitude of the currents reaching the 40 input circuit of the amplifier 7 decreases as the brushes 5 and 6 are moved towards the right, away from the terminals 8, 9.

For the present it will be assumed that the brushes 5 and 6 have been adjusted to the extreme left-hand position so that the currents 45 in the output circuit of amplifier 7 have their maximum value for the purpose of operating the reproducer 10 at the loudest degree of volume. Accordingly, the allowable ratio of 50 surface noise to useful sound is small and the different frequency components must be transmitted to reproducer 10 according to curve C' of Fig. 2. For the purpose of thus attenuating the higher frequency components, 55 a combination of electrical elements such as disclosed in United States patent to G. A. Campbell, No. 1,227,113, of May 22, 1917, may be employed. One form of network for this purpose is disclosed in Fig. 3 and comprises 60 the variable inductance 11 and the variable

capacitance 12. While in the drawing separate adjustments are indicated for varying the capacity and inductance, it will be understood that the values of these elements may be so chosen that the currents from the amplifier 7 70 may be attenuated in accordance with curve C' by a single adjustment.

Should it be desired to operate the reproducing system at a lower volume level, brushes 5 and 6 are moved toward the right to correspondingly reduce the energy level of the currents reaching amplifier 7. As mentioned above, at low volume reproduction less surface noise equalization is required, so that inductance 11 and capacity 12 may be varied to give 80 an over-all transmission characteristic represented by curve A'. Brushes 5, 6 and the inductance 11 and capacity 12 are preferably provided with suitably calibrated scales so that an attendant may adjust the brushes 5, 6 to give the desired volume of reproduction and at the same time adjust the inductance 85 and capacity to corresponding values.

Fig. 4 of the drawing shows a network and amplifier for producing variable equalized volume-transmission characteristics similar to those obtained with the apparatus of Fig. 2. In Fig. 4 the volume of sound from the reproducer, which is a function of the gain of the amplifier 17, is controlled by the variable resistance 14 which is connected in parallel with the variable inductance 15 and the variable capacitance 16. The means for varying the resistance, inductance and capacity may take the form of a plurality of wipers mounted on a common shaft and adapted to contact with different sections of the associated electrical elements 14, 15 and 16. Thus by a single adjustment of this shaft the volume of reproduction and the equalization for volume-frequency distortion may be controlled.

Fig. 5 shows an arrangement similar to that of Fig. 4 except that the electrical elements of the amplifier-network are connected in shunt with the current source. In this figure also it is preferable to have all the electrical elements arranged for simultaneous adjustment by a single manipulation.

While in the foregoing description and in the drawings the invention is disclosed in connection with a reproducing system employing one particular type of sound record, it is to be understood that the invention is equally applicable to systems using other types of records which, because of their mechanical or structural characteristics, tend to introduce undesirable noises into the reproduction. For example, in systems using photographic film records and light responsive devices, due to the non-homogeneity of the crystalline structure of the photographic emulsion, varying thicknesses of film and other similar causes, variations are introduced into the response of the light-sensitive device 115 which have no relation to the actual sound 120

recorded. These undesirable variations are of the same character and may be equalized in a similar manner to the variations in the surface of a wax or disc-type record. In the 5 following claims it will be understood, therefore, that the term "surface noise" is employed in its most generic sense. Furthermore, while there is shown a specific type of network for equalizing for volume-frequency 10 distortion, it is understood that the disclosure is essentially schematic in this respect, as any form of equalizer may be employed without departing from the spirit and scope of the invention.

15 What I claim is:

1. In a sound recording and reproducing system, means for artificially generating sound modulated currents, an electron discharge device for amplifying said currents, 20 means for varying the gain of said device, a variable electrical net work for variably attenuating the frequency components of said currents, and means for adjusting the gain of said amplifier and for simultaneously adjusting said net work.
2. In an artificial sound reproducing system, an element having a surface cutting to correspond with sounds to be reproduced, means for translating said cutting into corresponding electric currents, said currents having undesirable characteristics corresponding to the surface characteristics of said element, means for amplifying said currents, a sound reproducer operated in accordance 30

with said currents, and means for varying 35 the attenuations of the frequency components of the amplified currents according to their degree of amplification.

3. In a sound reproducing system, the combination of an element carrying a record of 40 sounds to be reproduced, a device for translating said record into corresponding electric currents, a sound reproducer controlled by said currents, an electron discharge amplifier, a network for selectively attenuating the 45 components of said currents and means effective by a single adjustment to vary the gain of said amplifier and for simultaneously varying said network in accordance with the variation in gain to preserve the faithfulness 50 of reproduction at any desired volume.

4. In a sound reproducing system, the combination of an element carrying a record of 55 sounds to be reproduced, means for translating said record into corresponding electric currents, said currents having undesirable characteristics corresponding to physical characteristics of said element, means for amplifying said currents, a sound reproducer operated in accordance with said currents, 60 and means for varying the attenuation of the frequency components of the amplified currents according to their degree of amplification.

In testimony whereof, I have signed my 65 name to this specification, this 20th day of May, 1927.

J. LOUIS REYNOLDS.
